UNITED STATES PATENT OFFICE

165,818

COASTER

Thomas E. Betner, Wayne, Pa.

Application May 3, 1951, Serial No. 15,060

Term of patent 14 years

(Cl. D44—10)

To all whom it may concern:

Be it known that I, Thomas E. Betner, a citizen of the United States, residing at Wayne, in the county of Montgomery and State of Pennsylvania, have invented a new, original, and ornamental Design for a Coaster, of which the following is a specification, reference being had to the accompanying drawing, forming part thereof, in which:

Fig. 1 is a top plan view of a coaster showing my new design; and

Fig. 2 is a side elevational view partly in section thereof taken on line 2—2 of Fig. 1.

I claim:

The ornamental design of a coaster, as shown.
THOMAS E. BETNER,
